DESIGN FOR A TIP LID FOR SMOKER'S STAND

Onnie Mankki, Cleveland, Ohio, assignor to Smokador Manufacturing Co., Inc., Bloomfield, N. J., a corporation of Delaware

Application July 7, 1945, Serial No. 120,567

Term of patent 14 years

(Cl. D85—2)

To all whom it may concern:

Be it known that I, Onnie Mankki, a citizen of the United States, residing at Cleveland, in the county of Cuyahoga and State of Ohio, have invented a new, original, and ornamental Design for a Tip Lid for Smoker's Stand, of which the following is a specification, reference being had to the accompanying drawing, forming part thereof, in which—

Fig. 1 is a top plan view of a tip lid for smoker's stand, showing my new design.

Fig. 2 is a view in side elevation of the tip lid shown in Fig. 1.

Fig. 3 is a bottom plan view of the tip lid shown in Fig. 1.

I claim:

The ornamental design for a tip lid for smoker's stand, substantially as shown.

ONNIE MANKKI.
